COLLAR

Angelo M. Panettieri, Bridgeport, Conn.

Application February 24, 1939, Serial No. 258,213

6 Claims. (Cl. 2—131)

The present invention relates to an improvement in collars, particularly of the fold down type comprising a band portion and a flap portion, and is a continuation in part of my application for Collar, Ser. No. 228,295, filed Sept. 3, 1938. The invention is especially concerned with collars of the so-called fused type in which a stiffening inter-liner is adhered or cemented between the outer layers of the collar, such inter-liner being of one of the well-known types, in which cellulose acetate or other suitable substance is incorporated, and which is subjected to the action of a reagent, or to the application of heat, to cause such inter-liner to adhere to adjacent layers of the collar.

In collar constructions heretofore in use employing a fused type inter-liner considerable difficulty has been experienced in maintaining the proper fold line, in securing a natural and comfortable fit of the collar, and in preventing breaking and cracking at the fold. Also the manufacture of such collars has been difficult due to the complication of stitching of various portions together, and the turning and finishing of the collar after such stitching.

It is an object of the present invention to obviate these difficulties, and to this end it is proposed, in the illustrated embodiment of the invention, to provide a stiffening inter-liner within the band portion of the collar, and a stiffening binding folded about its upper edge, and which is adapted to be secured to one of the outer layers of the collar by a line of stitching extending along such upper edge. This stiffening inter-liner within the band is not formed of a fuse type material, but is formed of a relatively coarse stiff lining material which will give sufficient body to the band of the collar while allowing it to remain relatively flexible and neck conforming. This flexibility, as will hereinafter more fully appear, enables the flap portion of the collar to be folded down and the collar curved into neck conforming shape without producing kinks or bulges along the fold line. The binding strip along the upper edge of the band lining provides an equalized stiffening reinforcing disposed at both sides of the band lining, which provides a positive fold line secured to one of the outer layers of the collar, so that there can be no shifting of such fold line. Due to the equalized arrangement of the binding at each side of the lining the collar may be curved into neck conforming shape without kinking, as distinguished for instance from a fold line formed

by a folded margin provided upon the upper edge of the band lining.

A further object is to provide the inter-liner of the band with a notched structure in relation to each of the angle corners between the flap and band portions at the ends of the collar, where the fold of the flap portion terminates, and whereby these portions of the collar are rendered extremely thin and flexible and free from any bulges, with the result that the fold of the flap of the collar will remain smooth and even, and the ends of the flap will fall in natural lines from the fold. The notches provided in the band also provide a clearance space within the band into which the seamed edges of the material will extend when the collar is turned.

A further object is to provide a stiffening inter-liner within the flap portion of the collar which is secured to one of the outer layers by a line of stitching disposed below the line of stitching securing the band lining to the other outer layer, and whereby when the collar is fused the upper portion of the band lining containing the reinforcing binding will be fused at one side to the inter-liner and to the outer layer which forms the face of the collar, the other side of the band lining being free from fusing to provide a yieldable bight for the folded flap, and whereby the flap may be positively folded about the fold line formed by the stiffening binding without any tendency to kink or pucker.

Another object is to provide a collar in which each of the outer layers of the collar is formed from a single piece of material free from any overlap seam along the fold line, so that the thickness at the fold line is reduced, and there is no sharp edge at the fold such as would be produced by an exposed seam.

A further object is to provide stiffening means incorporated in the end edges of the flap portion which will effectually maintain these edges in relatively straight lines.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is an inside plan of one of the outer layers, namely the face forming outer layer, and the stiffening inter-liner of the flap portion secured thereto by a line of stitching, one end of

the inter-liner being shown unsecured and folded back.

Fig. 2 is a vertical sectional view taken along the line 2—2 of Fig. 1.

Fig. 3 is an inside plan of the other outer layer, namely, the back forming layer, and the inter-liner of the band portion secured thereto by a line of stitching, one end of the inter-liner being shown unsecured and folded back.

Fig. 4 is a vertical sectional view taken along the line 4—4 of Fig. 3.

Fig. 5 is a plan view showing the face and back forming sections of the collar together with the inter-liners stitched together in wrong side out arrangement, one end of the collar being shown turned right side out.

Fig. 6 is a detail plan view showing the stiffening member employed for stiffening the end of the flap portion.

Fig. 7 is a side elevation of one end portion of the completed collar after the seam has been turned, as shown in Fig. 5, with finishing stitches applied and the flap inter-liner fused.

Fig. 8 is a side elevation of the completed collar shown in Fig. 7 with the flap folded down.

Fig. 9 is a vertical sectional view, on an enlarged scale, taken along the line 9—9 of Fig. 5, and showing the collar before turning.

Fig. 10 is a vertical sectional view, taken along the line 10—10 of Fig. 5, and showing the turned collar.

Fig. 11 is a vertical sectional view, taken along the line 11—11 of Fig. 7, showing the completed fused collar, the dot-and-dash lines showing the manner in which the flap is folded.

Fig. 12 is a transverse sectional view, taken along the line 12—12 of Fig. 5, and showing the end of the flap before turning.

Fig. 13 is a transverse sectional view, taken along the line 13—13 of Fig. 7, and showing the end of the flap after turning and completion of the collar.

Fig. 14 is a transverse sectional view taken along the line 14—14 of Fig. 7, showing the corner structure of the end of the fold line.

Similar reference characters indicate corresponding parts throughout the several figures of the drawing.

Referring to the drawing the outer layers 10 and 11 which form the face and back surfaces of the finished collar, and which are made from any suitable shirt or collar material, each comprise a one-piece band and flap portion, the upper and lower edges of these layers being suitably curved to provide the necessary fit, and the ends of the flap portions being cut along the straight lines 12 and 13 respectively, and the ends of the band portions being cut along the projecting and convexly curved lines 14 and 15 respectively.

The inter-liner 16 for the flap portion of the collar may be constructed of any suitable lining material. In the case of processed or fused collars it will be of a suitable processing material, that is, it will be woven with threads of celanese or cellulose acetate, or any other well known materials, which when subjected to a processing step, such as treatment with a solvent or application of heat, causes the inter-liner to adhere to the adjacent layers of the collar, and thus provide a stiffened wilt-proof structure which does away with the necessity for starching. While the present structure is particularly advantageous for use with this type of processed inter-lining, and eliminates many disadvantages heretofore

experienced in the use of such inter-liners, it will be understood that it is not limited to such use.

The inter-liner 16 corresponds in shape to the flap portion of the outer facing layer 10, except that at its lower edge it is extended to provide a marginal portion extending into the band portion for cooperation with the inter-liner of the band portion, as will hereinafter more fully appear. The corners of the inter-liner 16 are transversely cut, as at 17 to facilitate turning of the points of the finished collar, as will hereinafter more fully appear. The inter-liner 16 is secured to the face forming outer layer 10 by a row of stitching 18 extending adjacent the lower edge of the inter-liner.

The inter-liner 19 of the band portion of the collar is preferably formed from a much stiffer material than the inter-liner 16, and corresponds in shape to the band portion of the back forming outer layer 11. Near each end of the band inter-

liner 19 there is provided in its upper edge a V-shaped notch 20, the outer edge of which is outwardly spaced from the corner formed between the end edges 13 and 15 of the outer layer, and the inner edge of which is inwardly spaced from this corner, to provide an area at each end of the fold line of the collar extending downwardly into the band portion which is free of the lining material 19, for a purpose as will hereinafter more fully appear. The upper edge of the band inter-liner 19 is provided with a binding strip 21, of inverted U-shape in cross-section, which is engaged about each side of the upper edge and secured by a row of stitching 22, this binding strip extending at its ends to the inner ends of the notches 20. The inter-liner 19, with the binding strip 21 stitched thereon, is secured to the back forming outer layer 11 by a line of stitching 23 extending adjacent the upper edge of the strip 21. The lower edges of the inter-liner 19 and the band portion of the outer layer 11, which edges conform to each other, are folded upwardly to form a hem 24, which is secured by a line of stitching 25.

The face forming outer layer 10, with its flap 45 inter-liner 16 secured thereto, and the back forming outer layer 11, with its band inter-liner 19 secured thereto, are placed in overlying registering relation, with the outer surfaces of the outer layers 10 and 11 contacting each other, as shown 50 in Figs. 5 and 9. A stiffening member 26 of angular shape, and preferably formed of the same fusible material as the inter-liner 16, is engaged with the flap portion of the collar at each end contiguous to the straight edges 13—13 of the 55 back forming outer layer 11, the two leg portions of this member being folded along their center lines as shown in Fig. 5, to provide double thicknesses along the end edges 13 of the flap and along the longitudinal edge for a short distance, 60 the connecting portion between the leg portions, and which is disposed at the point of the flap, being of a single thickness. The assembled portions are thereupon stitched together by a row of stitching 27 extending adjacent the longitudinal edge of the flap portions and which also secures the longitudinal leg portions of the members 26, and by rows of stitching 28 at each end of the collar which extend adjacent the straight edges 12, 13 and the curved edges 14, 15, these 70 rows of stitching also securing the end leg portions of the members 26. The corners between the edges 12, 13 and 14, 15 are notched out, as at 29, the notches extending just short of the stitching 28. These notches facilitate turning the 75

collar at the corners. The collar is turned, as shown at the left hand side of Fig. 5 and in Fig. 10, the stitching 27 and 28 being concealed by the turning. Due to the notching at 29 the edges of the material which are turned in by the turning process lie flat at the corners, and in cooperation with the notches 20 produce relatively thin non-bulging structures at the ends of the fold line, and as shown by the sectional view, Fig. 14.

After turning of the collar a finishing line of stitching 30 is provided adjacent the longitudinal edge and the end edges of the flap portion, this line of stitching being inwardly of the inturned edges of the flap portion. The collar is next suitably processed to cause the inter-liner 16 to fuse with the face and back forming outer layers 10 and 11. The lower marginal portion of the inter-liner 16 which extends into the band portion also fuses with the upper portion of the band inter-liner at one side, while the other side of the band inter-liner which is adjacent the band portion of the back forming outer layer 11 is not fused and thus remains flexible to provide a yielding bight for the folded down flap of the collar, as shown in dot-and-dash lines in Fig. 11, thus permitting the face forming outer layer 10, which is fused entirely throughout the flap portion and for a short distance into the band portion, to be folded without resistance from the back forming outer layer. The line of stitching 18 in the finished collar is slightly inwardly offset through the interposition of the binding strip 21 above this line of stitching, and consequently there are no projecting stitches along the inner neck engaging surface of the collar which might tend to irritate the skin of the wearer.

I have illustrated and described a preferred and satisfactory embodiment of the invention, but it will be obvious that changes may be made therein within the spirit and scope thereof, as defined in the appended claims.

Having thus described my invention what I claim and desire to secure by Letters Patent is:

1. In a turned collar, a pair of outer layers of fabric, one being a face forming layer and the other a back forming layer and each comprising a band portion and a flap portion, the ends of the band portions extending beyond the ends of the flap portions, a stiffening flap inter-liner disposed between said flap portions having a lower marginal portion extending between said band portions, and secured by a line of stitching adjacent its lower longitudinal edge to the band portion of the inturned side of said face forming layer, a stiffening band inter-liner disposed between said band portions and secured by a line of stitching adjacent its upper longitudinal edge to the

band portion of the inturned side of said back forming layer, said lower marginal portion of said flap inter-liner overlapping the upper marginal portion of said band inter-liner at the side of said band inter-liner away from said back forming layer, the upper edge of said band inter-liner constituting an abutment about which the flap portion of the collar is folded down. 5

2. The invention as defined in claim 1, further characterized in that said flap inter-liner is formed of fusible material whereby said overlapping portions of said flap and band inter-liners are unsecured to each other except by fusing. 10

3. The invention as defined in claim 1, further characterized in that said flap inter-liner is formed of fusible material and said band inter-liner is formed of non-fusible material, said flap inter-liner being contactingly engaged with the flap portion of said back forming outer layer, and said non-fusible band inter-liner being interposed 20 between said overlapping lower marginal portion of said flap inter-liner and the band portion of said back forming layer, whereby said back forming layer is fused to said flap inter-liner only in its flap portion and is unfused in its band portion. 25

4. The invention as defined in claim 1, further characterized by notches in the upper edge of said band inter-liner respectively contiguous to the ends of said flap portion extending downwardly into the band from the fold line having their inner edges inwardly spaced from the stitching lines of the inturned stitched hems at the end edges of the collar and providing an area at each end of the fold line within the band which is free 35 of said band inter-liner. 30

5. The invention as defined in claim 1, further characterized by a stiffening strip folded over the upper edge of said band inter-liner and secured by a line of stitching independent of the 40 line of stitching securing said band inter-liner to said back forming layer.

6. The invention as defined in claim 1, further characterized by notches in the upper edge of said band inter-liner respectively contiguous to 45 the ends of said flap portion extending downwardly into the band from the fold line having their inner edges inwardly spaced from the stitching lines of the inturned stitched hems at the end edges of the collar and providing an area 50 at each end of the fold line within the band which is free of said band inter-liner, and a stiffening strip folded over the upper edge of said band inter-liner having its ends terminating contiguous to and at the inner sides of said notches. 55

ANGELO M. PANETTIERI.
